UNITED STATES PATENT OFFICE.

CHARLES W. HELTON, OF ELMHURST, ILLINOIS.

ASH-SIFTER.

1,286,620.

Specification of Letters Patent.

Patented Dec. 3, 1918.

Application filed May 20, 1918. Serial No. 235,536.

To all whom it may concern:

Be it known that I, CHARLES W. HELTON, a citizen of the United States, residing at Elmhurst, in the county of DuPage and 5 State of Illinois, have invented certain new and useful Improvements in Ash-Sifters, of which the following is a specification.

This invention is an ash sifter and has for its principal object the production of 10 efficient means for sifting the ashes in the pit of a furnace and then removing the coals and allowing the same to be placed where desired.

Another object of this invention is the 15 production of an ash sifter provided with a wheel which will support the weight of the sifter when the same is in use, although after the ashes have been sifted the remaining coal may be deposited where desired.

20 Another object of this invention is the production of an ash sifter wherein the sifter is operated somewhat similarly to a shovel and has a handle extending therefrom for facilitating its operation, while a 25 wheel is connected to the handle directly in the rear of the sifter body, thus permitting the sifter body to be inserted into an ash pit without interference from the supporting wheel.

30 Broadly stated, this invention consists of a sifter body including a substantially rectangular frame, said frame having a blade at its end for facilitating the scooping of ashes thereonto, a sifting bottom carried by 35 the frame, shanks extending from the rear portions of the frame, a handle carried by said shanks, V-shaped supporting brackets carried by said shanks and handle at the junction thereof, and a wheel carried by said 40 brackets for supporting the sifter body, said wheel being in the rear of the sifter body, thus being out of the way when ashes are being sifted and also permitting of the insertion of the sifter body into an ash pit 45 without interference from the wheel.

One practical form of construction and assembly of the present invention will be hereinafter described and is illustrated in the accompanying drawing, in which—

50 Figure 1 is a central longitudinal section through the body, the wheel supporting bracket and handle being shown in elevation, and

55 Fig. 2 is a top plan view of the ash sifter. In the preferred embodiment of the present invention, about to be described, 5 indi-

cates the frame of the sifting body. This frame comprises similarly constructed sides 6 having inwardly extending bridges 7 at their inner ends. Each bridge 7 is provided 60 with a shank 8 extending rearwardly therefrom and it will be noted by referring to Fig. 1, that the shank 8 extends slightly upwardly. The construction of the sides and bridges constitute a substantially rectangular body, which in practical use is of substantially the same size as the door of the ash pit, thus permitting the body to be readily inserted through the door opening 65 without interference.

The blade at the forward end of the sifting body indicated at 9, is substantially U-shaped, as shown in Fig. 1. It will be noted that this blade 9 is extended at an angle or projects in a plane which crosses 70 the longitudinal axis of the sifting body, thus compensating for the tilting of the sifting body when the same is inserted into the ash pit. By the diagonal extension of this blade it will be seen that when the forward end of the body is tilted downwardly, the blade will then rest flat upon the bottom 75 of the ash pit and for this reason will easily pass under the ashes of the pit.

A wire mesh bottom 10 is secured to the 80 sides 6 and bridges 7 in any suitable manner, while the U-shaped blade 9 is clamped upon the forward end of the wire, as illustrated in Fig. 1. Thus it will be seen that the entire portion of the sifting body has 85 a mesh in engagement therewith, although the sides and bridges extend for considerable distance above the wire mesh 10, thus preventing side displacement of the ashes or coals.

90 The handle 11 has its lower end extending through the shank 8 and is held in position by the rivets 12. Thus it will be seen that the handle 11 may be gripped for operating the sifting body somewhat similarly 95 to the mode of operating a shovel.

A V-shaped bracket 13 is carried upon 100 each shank 8 and these V-shaped brackets 13 are also retained in position by the rivets 12. A stub axle bolt 14 is carried by the apices of the brackets 13 and the wheel 15 is carried upon this bolt. Particular attention is invited to the fact that this wheel is 105 carried directly beneath the forward end of the handle and in the rear of the body. Accordingly, the wheel will not be positioned 110 so as to be clogged by the ashes falling there-

on and a very important feature resides in the placing of the wheel in the rear of the body, to allow the body to be easily inserted in an ash pit without interference from the wheel. As is commonly known, the bottom of the air pit is built up slightly above the floor or supporting surface upon which the furnace or boiler is carried and for this reason if a wheel were carried directly under the sifting body it would interfere with the easy passing of the sifting body into the ash pit. However, by mounting the wheel of the present invention in the rear of the body, the body may be easily passed through the door opening and will easily dig into or scoop up the ashes without interference from the wheel.

In operation, the device is of a dustless nature, since the sifting of the ashes actually takes place in the ash pit and the draft will take away the dust without allowing the same to escape through the door opening of the ash pit. Accordingly, the handle is tilted to bring the blade 9 into the bottom of the ash pit and then by forward movement the ashes will be shoveled or scooped onto the sifting body. A reciprocal stroke of the handle will cause like movement of the sifting body and will thus cause the ashes to be sifted through the wire mesh 10 although the coals will be retained on this wire mesh.

The sifting body may then be drawn from the ash pit and the handle may be lifted to lift the sifting body at which time the coals carried upon the sifting body may be deposited wherever desired.

When the sifting operation is taking place, it is obvious the weight of the sifting body and the ashes thereon will be supported by the wheel 15 which rides in either direction according to the direction of movement of the ash sifter. It is also obvious that the device may be used in a manner similar to the use of a shovel and that when used as a sifter and the sifting body is carried within the ash pit, no objectionable dust, which ordinarily occurs will be noticed.

The foregoing description and the drawings have reference to what may be considered the preferred, or approved, form of my invention. It is to be understood that I may make such changes in construction and

arrangement and combination of parts, materials, dimensions, et cetera, as may prove expedient and fall within the scope of the appended claims.

Having thus fully described my invention, what I claim as new and desire to secure by Letters Patent, is:—

1. In an ash sifter, the combination of a sifting frame, a handle extending from said sifting frame, and a supporting means carried by said handle at a point in the rear of and spaced from the sifting frame, whereby the sifting frame will be supported at a distance above the supporting surface and will be unobstructed throughout its entire length.

2. In an ash sifter, the combination of a sifting frame, a handle connected to said frame, brackets carried by said handle and spaced from the sifting frame and a wheel connected to said brackets, whereby the wheel will be connected to the handle at a point in the rear of the sifting frame, thus causing the sifting frame to be supported above the supporting surface and be unobstructed throughout its entire length.

3. In an ash sifter, the combination of a sifting frame including parallel shanks extending rearwardly therefrom in spaced apart relation, a handle inserted between said shanks, supporting brackets comprising side members which converge toward their lower ends to form apices, the upper portions of said brackets bearing in spaced apart relation upon said shanks, securing means extending through said brackets and said shanks and handle for fixing these elements upon each other, a stub-axle carried at the apices of the brackets and a wheel rotatably mounted upon said stub axle between said brackets, thus causing the wheel to be connected to said handle at a point in the rear of the sifting frame, whereby the frame will be supported above a supporting surface and will be unobstructed throughout its entire length.

In testimony whereof I affix my signature in presence of two witnesses.

CHARLES W. HELTON.
